UNITED STATES PATENT OFFICE.

JABEZ KLIF, OF FERGUS FALLS, MINNESOTA.

ATTACHMENT FOR SQUARES.

SPECIFICATION forming part of Letters Patent No. 366,404, dated July 12, 1867.

Application filed January 6, 1867. Serial No. 223,558. (No model.)

To all whom it may concern:

Be it known that I, JABEZ KLIF, of Fergus Falls, in the county of Otter Tail and State of Minnesota, have invented a new and Improved 5 Measuring-Instrument, of which the following is a full, clear, and exact description.

The object of my invention is to provide a new and improved measuring-instrument especially adapted for the use of carpenters, 10 stair builders, &c.

The invention consists of a square and two slotted straight-edges adapted to be fastened on the said square by means of bolts.

The invention also consists of various parts 15 and details and combinations of the same, as will be fully described hereinafter, and then pointed out in the claims.

Reference is to be had to the accompanying drawings, forming part of this specification, 20 in which similar letters of reference indicate corresponding parts in all the figures.

Figure 1 is a face view of my improvement as applied for finding the center of a circle. Fig. 2 is an edge view of the same. Fig. 3 is a 25 face view of my improvement, showing it applied for laying out mortises. Fig. 4 is a face view of a modified form of my improvement adapted for laying out radial lines of cylinders, and Fig. 5 is a face view of a modified form of my improvement adapted for laying 30 out stair-stringers.

My instrument is provided with a square, A, having the usual arms, B and C, each provided with a slot, B' or C', respectively, in its 35 middle, of which the slot C' extends from near the outer end to the middle of the other arm, B, as shown plainly in Fig. 3.

On the square A are placed two straight-edges or rules, D and E, each having a central 40 slot, D' or E', respectively, and offset-grooves D² and E² at each side of the said respective slots D' and E'. Through the slots in the square and in the straight-edges pass the bolts F, by which the said square and the straight-edges are held together. The bolts F, with 45 their respective heads, can be easily removed from or placed on the said square and straight-edges by passing the same through the enlarged round apertures formed at the outer 50 ends of the slots in the said square and the

straight-edges. The heads of the bolts F are held in the grooves D² and E², and do not project above the respective faces.

The faces of the square A are provided with the usual graduation of inches and subdivisions of the same, and one of the straight-edges is provided on its under side with a lumber-measure, and the other straight-edge is provided on its under side with an octagon measure or points. The upper faces of both straight-edges D and E are marked with the usual 55 graduations of inches and subdivisions of the same.

The instrument is used as follows: For obtaining the center of a circle, I fasten the straight-edge E upon the arms B and C of the square A by means of two bolts and at an angle of forty-five degrees, as shown in Fig. 1. I then fasten the other straight-edge, D, with one bolt, F, to the arm B of the square by inserting the said 60 bolt into an aperture, B², in the said arm B, so that when one edge of the said straight-edge D is placed at the junction of the inner edges of the square-arms B and C, as shown in Fig. 1, then the straight-edge D stands at an angle 65 of forty-five degrees to both arms and at right angles to the other straight-edge, E. The center of any given circle can then be found, as the straight-edge D will always pass through the center of the circle when the inner edges 70 of the arms B and C are placed as tangents of the circle, as shown in Fig. 1. The exact center is then easily marked by the other straight-edge.

For laying out mortises, I arrange the instrument, as shown in Fig. 3, by placing one straight-edge, E, at right angles to the arm B of the square A, and the other straight-edge, D, at right angles to the other arm, C, and then fasten the straight-edges together at their junction by a 75 bolt, F. The straight-edges are placed at such distances apart as to correspond with the sizes of the mortises and with the distances that the mortises should be apart. The latter are then marked off on the inner edges of the 80 arms of the square, and on the inner edges of the straight-edges, as shown in Fig. 3.

For laying out radial lines of a cylinder, I attach upon one of the straight-edges D the head I, provided on each side with a slot, I', 85

in which is held, by means of a bolt, K, a short slotted arm, J, having its inner end rounded off. The arms J are set parallel to the straight-edge D, which is at right angles to the head I, 5 and the said arms J are placed at equal distances from one of the edges of the straight-edge D, so that when the instrument is applied internally or externally to a cylinder, as shown in Fig. 4, then one edge of the straight-edge D will mark the radial lines of the said cylinder. It can also be used as a T-square.

For laying out stair-stringers, I use both the straight-edges and the square, as shown in Fig. 5, and I set the straight-edges D and E to 15 the pitch of the stringer, and the arms of the square horizontally and vertically, respectively, so that the outer edges of the arms serve to mark the vertical and horizontal lines for the steps, while one edge of the straight-edges 20 rests against the stringer, as shown in Fig. 5. The straight-edges D and E are placed over each other and are used as one straight-edge.

I may also use a square without slots and fasten the straight-edges on the arms of the 25 square, as shown in Fig. 5, by passing the bolts F through the rules near the edge of the

square. The instrument may be used in various other ways—such as ascertaining the height of a building, length of rafters, braces, &c.

Having thus fully described my invention, I claim as new and desire to secure by Letters Patent—

1. The combination, with a slotted square, of the slotted straight-edges connected to said square and to each other by the bolts or pins adjustable in the slots of the square and straight-edges, substantially as and for the purpose set forth. 35

2. The combination of the square A, provided with the arm B, having the slot B', and the aperture B², and the arm C, having the slot C', of the straight-edges D and E, having the slots D' and E', respectively, and the grooves D² and E², respectively, and the bolts F, for 40 fastening the said square and straight-edges together, substantially as shown and described. 45

JABEZ KLIF.
